UNITED STATES PATENT OFFICE.

MILTON D. MESEROLE, OF WEST HAVEN, CONNECTICUT, ASSIGNOR TO THOMAS F. MOLLOY AND LILLIAN MOLLOY SHEEHAN, OF NEW HAVEN, CONNECTICUT, ADMINISTRATORS OF JAMES F. MOLLOY, DECEASED.

BUCKLE.

1,089,853.

Specification of Letters Patent. Patented Mar. 10, 1914.

Application filed December 8, 1913. Serial No. 805,380.

To all whom it may concern:

Be it known that I, MILTON D. MESEROLE, a citizen of the United States, residing at West Haven, in the county of New Haven, and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Figure 1 a top or plan view of a buckle constructed in accordance with my invention. Fig. 2 an underside view of the same. Fig. 3 a side view. Fig. 4 a longitudinal sectional view showing the clamping-piece in the retired position. Fig. 5 a similar 20 view showing the clamping-piece engaged with the strap. Fig. 6 a plan view of the clamping-piece, detached. Fig. 7 a sectional view of a modified form of back-plate.

This invention relates to an improvement 25 in buckles, and while adapted for various purposes, it is particularly designed for use as a belt buckle, and to that class of belt buckles which comprise a plate, a housing, and a sliding clamping-piece within the 30 housing.

The object of this invention is to form the sliding piece with a spring finger which will bear upon the plate or bottom of the chamber and so as to adapt the buckle for 35 use with straps of varying thicknesses; and the invention consists in certain details of construction and combinations of parts as will be hereinafter described and particularly recited in the claims.

In carrying out my invention, I form 40 the buckle from a plate 2 formed near its rear end with a central clearance space or opening 3, and preferably and as herein shown, the forward edge of the opening is turned down forming a lip 4. Secured to 45 the plate is a housing 5 formed on opposite sides with slots 6 through which project finger-pieces 7 formed at opposite sides of a clamp 8 the edges 9, 10, of which project 50 toward the upper wall of the housing. The forward edge of this clamping member is formed with a spring-finger 11 which is turned toward the plate and its rear end bowed upward so as to have a bearing

against the bottom of the clamping-member. 55 The width of this spring-finger corresponds substantially to the width of the opening 3 formed in the plate so that when the slide is moved rearward this spring-finger will drop into the said opening so as to allow 60 the gripping edges 9, 10, to be freed from the strap 12. When the slide is moved forward, the spring finger engages with the lip 4 which tends to lift the clamping-piece, and as the clamping-piece is drawn forward 65 it is crowded into engagement with the strap inserted through the housing. The fixed end 13 of the strap is connected with the plate in any desired manner, such connection forming no part of the present in- 70 vention.

Instead of cutting away the metal to form the clearance space 3, the metal may be struck outward to form a clearance space or pocket 14 as indicated in Fig. 7. 75

When the strap is inserted into the housing, the clamping-piece is moved forward by means of the finger-piece 7 and the edges 9, 10, bite into the inner face of the strap 80 clamping the strap against the inner wall of the housing, and any strain upon the strap will tend to draw the clamping-piece forward and crowd it into still closer engagement with the strap, the spring-finger 11 bearing against the inner face of the 85 plate, will yield so that straps of varying thickness may be held. To release the strap it is only necessary to move the clamping-piece rearward so that the spring-finger 90 may drop into the clearance space or opening in the plate, thus giving clearance above the clamping-piece for the withdrawal of the strap.

I claim:—

1. A buckle comprising a plate formed 95 with a clearance space, a housing secured to said plate, said housing formed on opposite sides with slots, a clamping-piece within said housing and formed with finger-pieces projecting outward through said slots, 100 said clamping-piece provided with a spring-finger adapted to bear upon the said plate and to enter the clearance-space therein.

2. A buckle comprising a plate formed with a clearance opening near its rear end, 105 a housing secured to said plate and provided on opposite sides with slots, a clamping-piece within said housing and provided

with finger-pieces extending outward through said slots, said clamping-piece provided at opposite edges with gripping jaws, and with a spring-finger turned inward and rearward 5 from its forward edge and adapted to bear upon the inner face of the plate and to enter the opening formed therein.

In testimony whereof, I have signed this specification in the presence of two subscribing witnesses.

MILTON D. MESEROLE.
